CLAIM

The ornamental design for a ceiling fan motor housing as shown and described.

DESCRIPTION

This application is related to U.S. Utility patent application Ser. No. 16/251,453, filed Jan. 18, 2019, and U.S. Utility patent application Ser. No. 16/844,459, filed Apr. 9, 2020, all of which are incorporated herein by reference in their entirety.

FIG. 1 is a perspective view of a ceiling fan motor housing shown in an environment of a ceiling fan;

FIG. 2 is an enlarged perspective view showing detail 2 encircled in FIG. 1;

FIG. 3 is a top perspective view of the ceiling fan motor housing of FIG. 1, shown in an environment of a ceiling fan;

FIG. 4 is a bottom perspective view thereof;

FIG. 5 is top plan view of the ceiling fan motor housing of FIG. 1 shown without the environment;

FIG. 6 is a top perspective view thereof; and,

FIG. 7 is a right side elevational view thereof.

Broken lines illustrate portions of the ceiling fan motor housing that form no part of the claimed design. Additional broken lines in FIGS. 1-4 show environmental subject matter and form no part of the claimed design.
